Primary Examiner—Cathron C. Brooks*Assistant Examiner*—Austin Murphy(74) *Attorney, Agent, or Firm*—George R. McGuire; Bond Schoeneck & King, PLLC(57) **CLAIM**

The ornamental design for a binder, shown and described.

DESCRIPTION

FIG. 1 is a perspective view of a new and ornamental design for a binder;

FIG. 2 is a front elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is a rear elevation view thereof.

The broken lines depiction of the zipper attachment element and zipper pull forms no part of the claimed design. The remainder of the broken lines represent stitching.
